Primary Examiner—Freda S. Nunn

(74) Attorney, Agent, or Firm—Banner & Witcoff, Ltd.

(57) **CLAIM**

The ornamental design for a portion of a keyboard, as shown and described.

DESCRIPTION

FIG. 1 is a top perspective view of a portion of a keyboard showing my new design; and,

FIG. 2 is a top view thereof.

The broken line showing of the remainder of the keyboard is for illustrative purposes only and forms no part of the claimed design.

1 Claim, 2 Drawing Sheets

FIG. 1

FIG. 2
